(57) **CLAIM**

The ornamental design for a load control device, as shown and described.

DESCRIPTION

This application is related to U.S. patent application Ser. No. 29/449,250, filed on Mar. 14, 2013 and entitled “Load Control Device,” U.S. patent application Ser. No. 29/449,232, filed on Mar. 14, 2013 and entitled “Load Control Device,” U.S. patent application Ser. No. 29/449,242, filed on Mar. 14, 2013 and entitled “Load Control Device,” U.S. patent application Ser. No. 29/449,257, filed on Mar. 14, 2013 and entitled “Load Control Device,” and U.S. patent application Ser. No. 29/449,263, filed on Mar. 14, 2013 and entitled “Load Control Device.”

FIG. 1 is a perspective view of a first embodiment of a load control device embodying our new design;

FIG. 2 is a front view of the load control device of FIG. 1;

FIG. 3 is a first side view of the load control device of FIG. 1;

FIG. 4 is a second side view of the load control device of FIG. 1;

FIG. 5 is a top view of the load control device of FIG. 1;

FIG. 6 is a bottom view of the load control device of FIG. 1;

FIG. 7 is a perspective view of a second embodiment of a load control device embodying our new design;

FIG. 8 is a front view of the load control device of FIG. 7;

FIG. 9 is a first side view of the load control device of FIG. 7;

FIG. 10 is a second side view of the load control device of FIG. 7;

FIG. 11 is a top view of the load control device of FIG. 7; and,

FIG. 12 is a bottom view of the load control device of FIG. 7.

The rear view forms no part of the claimed design. Additionally, the rear view forms no part of the claimed design.
